UNITED STATES PATENT OFFICE.

JOSEPH J. DI NATALE, OF NEW YORK, N. Y.

DESIGN FOR A BUTTON, EMBLEM, BADGE, PIN, OR SIMILAR ARTICLE.

Application filed July 12, 1922. Serial No. 3,045. Term of patent 3½ years.

To all whom it may concern:

Be it known that I, JOSEPH J. DI NATALE, a citizen of the United States, residing in the city of New York, in the county of Bronx and State of New York, have invented a new, original, and ornamental Design for Buttons, Emblems, Badges, Pins, or Similar Articles, of which the following is a specification, reference being to the accompanying drawings, forming a part thereof, Figure 1 of which is a view in front elevation of a button or similar article and Fig. 2 is an edge elevation of the same, showing my new design.

I claim:

The ornamental design for a button, emblem, badge, pin, or similar article, as shown.

JOSEPH J. DI NATALE.
